UNITED STATES PATENT OFFICE.

HERBERT F. OBERGFELL, OF RIVER FOREST, ILLINOIS, ASSIGNOR TO AUTOMATIC ELECTRIC COMPANY, OF CHICAGO, ILLINOIS, A CORPORATION OF ILLINOIS.

DESIGN FOR A COMBINED RINGER BOX AND TELEPHONE DESK STAND.

Application filed October 10, 1925. Serial No. 15,081. Term of patent 14 years.

To all whom it may concern:

Be it known that I, HERBERT F. OBERGFELL, a citizen of the United States of America, residing at River Forest, in the county of Cook and State of Illinois, have invented a new, original, and ornamental Design for a Combined Ringer Box and Telephone Desk Stand, of which the following is a specification, reference being had to the accompanying drawings, forming a part thereof.

a combined ringer box and telephone desk stand, of the cradle-type, in perspective; and Fig. 2 is a side and partial top view in perspective.

What is claimed is:

The ornamental design for a combined ringer box and telephone desk stand, as shown.

In testimony whereof, I have hereunto set my hand this 6th day of October, 1925.

HERBERT F. OBERGFELL.
